CAM LAPPING MACHINE

Herbert S. Indge, Westboro, Mass., assignor to
Norton Company, Worcester, Mass., a corpora-
tion of Massachusetts

Application July 30, 1946, Serial No. 687,100

16 Claims. (Cl. 51—58)

1

The invention relates to lapping machines, and more particularly to a machine for lapping a plurality of cams on a cam shaft.

One object of the invention is to provide a simple and thoroughly practical cam lapping machine. Another object of the invention is to provide a cam shaft lapping machine in which the table for supporting the cam shaft and master cam shaft is supported for a relatively short reciprocatory stroke by means of flexible rubber bearings which permit a swinging movement of the table so as to eliminate friction and wear between metallic parts, and also to eliminate the necessity of lubrication. Another object of the invention is to provide a cam lapping machine covering a longitudinally reciprocable table which is provided with a positively rotated spindle and center to support a cam shaft to be lapped, and a second parallel spindle and center to support a master cam shaft parallel to the cam shaft being ground. A further object of the invention is to provide such a cam lapping machine with a motor driven driving mechanism which is arranged synchronously to rotate both the work supporting and the master cam shaft supporting spindles.

A further object of the invention is to provide pivotally mounted lapping arms which are arranged for a transverse and longitudinal swinging or rocking movement on non-wearing frictionless bearing supports so as to eliminate wear and the necessity of lubrication. Another object of the invention is to provide downwardly projecting substantially vertical lapping arms and follower arms for each of the cams to be lapped, in which the entire lapping arms assembly is arranged for a longitudinal swinging movement which is also supported by flexible rubber bearings to eliminate wear and lubrication. Another object of the invention is to provide a cam lapping machine in which the master cam shaft is identical with a finished lap cam shaft. Other objects will be in part obvious, or in part pointed out hereinafter.

The invention accordingly consists in the features of construction, combinations of elements, and arrangement of parts, as will be exemplified in the structure to be hereinafter described, and the scope of the application of which will be indicated in the following claims.

In the accompanying drawings, in which is shown one of various possible embodiments of the mechanical features of the invention:

Fig. 1 is a front elevation of a cam lapping machine embodying this invention;

2

Fig. 2 is a fragmentary plan view of the machine showing the foot stock;

Fig. 3 is a fragmentary sectional view, on an enlarged scale, taken approximately on the line 5—3—3 of Fig. 1, showing the connection for transmitting a longitudinal reciprocatory movement to the lapping arms;

Fig. 4 is a fragmentary vertical sectional view, on an enlarged scale, taken approximately on the line 10—4—4 of Fig. 1, showing the spindle driving mechanism and the table guiding mechanism;

Fig. 5 is a longitudinal sectional view, on an enlarged scale, taken approximately on the line 15—5—5 of Fig. 1, showing the arrangement of the cam shaft driving and the master cam shaft driving spindles;

Fig. 6 is a fragmentary sectional view, taken approximately on the line 20—6—6 of Fig. 5, showing the driver for the master cam shaft;

Fig. 7 is a fragmentary sectional view, on an enlarged scale, taken approximately on the line 25—7—7 of Fig. 1;

Fig. 8 is a vertical sectional view taken approximately on the line 25—8—8 of Fig. 7, showing a portion of the table reciprocating mechanism;

Fig. 9 is a diagrammatic end elevation of one of the flexible rubber bearings, on an enlarged scale;

Fig. 10 is a similar diagrammatic view of the bearing, illustrating how the rubber yields when the outer periphery of the bearing is oscillated in a counterclockwise direction;

Fig. 11 is a similar diagrammatic view of the bearing, showing how the rubber yields as the outer periphery of the bearing is moved in a clockwise direction;

Fig. 12 is a vertical sectional view on an enlarged scale, taken approximately on the line 40—12—12 of Fig. 1, showing the driving mechanism for imparting a longitudinal reciprocatory stroke to the lapping arms;

Fig. 13 is a sectional view partly in elevation, on an enlarged scale, taken approximately on the line 45—13—13 of Fig. 1, showing one of the pivotal supports for the lapping arm assembly;

Fig. 14 is a right-hand elevation on an enlarged scale, taken approximately on the line 14—14 of Fig. 1, showing one of the lapping arms and follower arms, partly broken away and shown in section, to more clearly illustrate the construction;

Fig. 15 is a horizontal sectional view, taken approximately on the line 50—15—15 of Fig. 14 through the guide for the lapping and follower arms;

Fig. 16 is a horizontal sectional view taken approximately on the line 55—16—16 of Fig. 14,

through the connecting link which connects the lapping arm with the follower arm; and

Fig. 17 is a fragmentary detail view of a portion of a modified form of the lapping arm adapted for use with flexible abrasive paper or cloth instead of a bonded abrasive element, as shown in Fig. 14.

A cam lapping machine has been illustrated in the drawings comprising a base 20, which supports a longitudinally movable table 21. The table 21 is provided with a head stock 22 and a foot stock 23. The head stock 22 is provided with a work rotating spindle 24, which is supported in anti-friction bearings 25 and 26 in the frame of the head stock 22. The spindle 24 is provided with a work driving head 27, which is provided with means including a driving key 27a (which is arranged) to support and rotate the left-hand end of a cam shaft 28. The other end of the cam shaft 28 is supported by a foot stock center 29, which is carried by the foot stock 23.

A suitable driving mechanism is provided for rotating the spindle 24 and the cam shaft 28 comprising an electric motor 30, which is mounted within the base 20 of the machine on a pivotally mounted platen 31. The platen 31 is pivotally supported on a rock shaft 32, which is in turn supported by the base 20. An adjusting screw 33 is provided for pivotally adjusting the platen 31 so that the position of the motor 30 may be varied as desired to provide the desired driving tension on the driving belt, to be hereinafter described. The motor 30 is provided with a multiple V-groove pulley 34 which is connected by multiple V-belts with a multiple V-groove pulley 36 which is supported on a rotatable shaft 37. The shaft 37 is supported in anti-friction bearings 38 and 39 carried by the head stock 22. A driving worm 40 is keyed to the shaft 37 and meshes with a worm gear 41 which is keyed on the work spindle 24. It will be readily apparent from the foregoing disclosure that rotary motion of the motor pulley 34 will be transmitted through the driving mechanism just described, to impart a rotary motion to the spindle 24 and the cam shaft 28.

A second spindle 45 is supported in anti-friction bearings 46 and 47 carried by the head stock 22. The spindle 45 is arranged parallel to the head stock spindle 24, and serves to support and rotate one end of a master cam shaft. The spindle 45 is provided with a driving head 48, which drivingly engages the left-hand end of a master cam shaft 49. The hand-hand end of the master cam shaft is supported by an aligned foot stock center 50 so that the master cam shaft is arranged and supported parallel to the cam shaft to be lapped.

In order to time the master cam shaft 49 relative to the cam shaft 28, a suitable adjusting mechanism is provided for the master cam shaft driver 48, which is illustrated in Fig. 6. The driver 48 is supported on a flanged support 48a. The driver 48 is provided with a plurality of symmetrically arranged elongated slots 48b. Clamping screws 48c pass through the elongated slots 48b and are screw threaded into the flanged member 48a. It will be readily apparent that the driver 48 may be rotarily adjusted relative to the flanged member 48 by means of the clamping screws 48c. In order to facilitate this adjustment, the flanged member 48a is provided with a projecting lug 48d and the driver 48 is provided with a pair of opposed aligned adjusting screws 48e and 48f which serve as push and pull screws to facilitate a precise adjustment of the driver 48 relative to the flanged member 48a.

When a relatively long cam shaft having a plurality of cams to be lapped is mounted in the machine, it is desirable to support the cam shaft and also the master cam shaft midway between the drivers and the foot stock centers by a steadyrest 51. This steadyrest has not been illustrated in detail, since any conventional steadyrest which is well known in the art may be utilized.

In order that the master cam shaft spindle 45 may be synchronously rotated with the head stock spindle 24, a suitable driving connection is provided comprising a gear 52, which is keyed on the head stock spindle 24. The gear 52 meshes with an idler gear 53, which in turn meshes with a gear 54. The gear 54 is keyed to the master cam shaft spindle 45. In order to take up back lash in the gearing above described, the idler gear 53 is preferably formed as a split gear so that one part thereof may be adjusted relative to the other to compensate for back lash between the gear teeth.

In order to attain one of the objects of this invention, it is desirable to provide a support for the work table 21 whereby the table may be moved longitudinally in a substantially rectilinear path, without the necessity of overcoming the friction between the common and well known table ways. In a cam lapping machine of the present type it is desirable to reciprocate the work support longitudinally through a relatively short stroke, which in the average case is not over $\frac{1}{8}$ to $\frac{1}{4}$ of an inch in length, in order to provide the desired breakup motion between the rotating cam to be lapped and the lapping element. In the preferred construction, the table 21 is preferably suspended by a suitable mechanism so that it may be swung in a longitudinal direction, thus eliminating the usual friction and wear of table ways and also eliminating the necessity for providing lubrication therefor. As illustrated in the drawings, the base 20 is provided with a pair of upwardly extending brackets 60 and 61 at the opposite ends thereof. The brackets 60 and 61 support pivot shafts 62 and 63. A pair of downwardly extending substantially vertical parallel rock arms 64 and 65 are supported by the pivot shafts 62 and 63. These rock arms are arranged in pairs, which are spaced as shown in Fig. 4 of the drawings. The rock arm 64 being arranged adjacent to the front face of the table and the rock arm 64a being arranged in alignment therewith but adjacent to the rear face of the table 21. A spaced arm is similarly provided at the rear of the machine in alignment with the rock arm 65. Pivot shafts 66 and 67 pivotally connect the rock arms 64 and 65 with the opposite ends of the table 21.

In order to eliminate the usual metal-to-metal pivotal connection between the rock arms and the pivot shafts, flexible rubber bearings are provided, which permit a rocking movement of the arms through the required angular motion. The flexible bearing is an indestructible union of concentric metal cylinders joined by a layer of rubber under pressure for the purpose of mounting or coupling machine parts or equipment in motion. These bearings depend upon a mechanical adhesion rather than a chemical bond to obtain efficient operation. As illustrated diagrammatically in Figs. 9, 10 and 11, these bearings comprise an outer metallic cylinder 69 and an inner metallic cylinder 70, between which is provided a layer of flexible rubber 71. These bearings may be of the well-known type such as is manufac-

tured by the General Tire and Rubber Company of Akron, Ohio.

The bearings are mounted so that the metallic outer and inner cylinders are fixedly mounted to one of the machine parts. When the outer cylinder is rocked in a counterclockwise direction, the rubber 71 yields, as indicated by the dotted lines in Fig. 10. Similarly, if the outer metallic cylinder is moved in a clockwise direction, the rubber layer 71 yields as indicated by the dotted lines in Fig. 11. One of these flexible rubber bearings is interposed between the pivot shafts 62, 63, 66 and 67 and the rock arms 64 and 65. The outer cylinder 69 of each bearing is fixed relative to the rock arms 64 and 65 and the inner cylinder 70 is fixed relative to the pivot shafts 62, 63, 66 and 67. It will be readily apparent from the foregoing disclosure that when the table 21 is moved in a longitudinal direction, a swinging motion will be imparted through the rock arms 64 and 65. By this construction a frictionless support is provided for the table 21, eliminating the standard type metal-to-metal type bearings, and also eliminating the necessity of providing lubrication therefor. Due to the fact that the table moves through a relatively short reciprocatory stroke, or not in excess of $\frac{1}{8}$ of an inch, the table will move in a substantially rectilinear path.

In order to guide the table 21 and prevent transverse motion thereof during reciprocation, a pair of links 77 and 77a are provided. One of these links 77 has been illustrated in detail in Fig. 4. The base 20 supports a stud 75 which carries a flexible rubber bearing 76. The inner part of the bearing is fixed relative to the stud 75 and the outer part is fixed relative to the link 77. A stud 78 is mounted on the table 21 and serves as a support for a flexible rubber bearing 79. The inner part of the bearing is fixed relative to the stud 78 and the outer part is fixed relative to the link 77.

The arrangement of the link 77a is identical with that just described in connection with the link 77, and therefore has not been illustrated and described in detail. As illustrated in Fig. 4, the stud 78 is provided with an eccentric portion 80 whereby the position of the table relative to the base may be adjusted in setting up the machine. It will be readily apparent that by providing a pair of parallel links 77 and 77a, the table 21 may be moved longitudinally, the links being free to swing due to the flexible rubber bearings, which serves to hold the table against transverse movement during its reciprocatory stroke.

A suitable motor driven mechanism may be provided for imparting a reciprocatory movement to the table 21. This mechanism may comprise an electric motor 81 which is connected to an integral gear reduction unit 82 to rotate a vertically arranged shaft 83. A head 84 (Fig. 8) is mounted on the upper end of the shaft 83 and serves as a support for an adjustably mounted crank pin 85. The crank pin 85 is provided with a roller 86. A needle bearing is preferably interposed between the crank pin 85 and the roller 86. The roller 86 rides in a transversely arranged elongated slot 87 formed in the under side of the table 21. In order to facilitate adjustment of the reciprocatory stroke of the table, the crank pin 85 is supported within an elongated slot 88 formed in the upper surface of the head 84. By loosening a nut 90 and adjusting a set screw 89, the crank pin 85 may be adjusted either toward or from the axis of rotation of the shaft 83 to increase or decrease the throw of the crankpin 85 as desired. When the motor 81 is started, a rotary

motion is imparted through the shaft 83, the head 84 to the crank pin 85. The crank pin 85 through the roller 86 transmits a longitudinal reciprocatory movement to the table 21.

In order to simultaneously lap a plurality of cams on the cam shaft 28, a plurality of spaced lapping arms 95, 96, 97 and 98 are provided. These lapping arms are all identical in construction, and consequently only one of these arms has been illustrated in detail in Fig. 14. The lapping arm 98 is pivotally supported by means of a stud 99 on a bracket 100. A flexible rubber bearing 101 is interposed between the lapping arm 98 and the pivot stud 99 so as to provide a frictionless bearing which permits the desired rocking movement of the lapping arm 98 during a lapping operation. The bracket 100 is provided with a clamping block 102 which, together with the upper surface of the bracket, forms a dovetailed clamping surface for adjustably clamping the bracket 100 in the desired adjusted position on a supporting member.

A lapping block 103 is pivotally supported by a stud 104 carried by the lapping arm 98. As illustrated in Fig. 14, a cylindrically shaped bonded abrasive lapping element 105 is supported by the block 103 and is arranged to operatively engage the cam 28 to be lapped. A compression spring 106 is carried by the arm 98, and serves to yieldably maintain the lapping element 105 in operative engagement with the cam being lapped during a lapping operation. A stop stud 107 is provided for limiting the swinging movement of the block 103 relative to the lapping arm 98.

A follower arm 108 is pivotally supported by means of a stud 109. A flexible rubber bearing 110 is interposed between the stud 109 and the follower arm 108. An adjustable bracket 111 is adjustably supported on the lower end of the follower arm 108, and serves as a support for a cylindrically shaped follower roller 112. The follower roller 112 is arranged to engage and follow the master cam 49a during rotation thereof. The follower roller 112 is preferably of a diameter equal to the diameter of the lapping element 105.

In order to connect the follower arm 108 with the lapping arm 98, a connecting link 113 is provided, which is connected by means of a stud 114 to the follower arm and by means of a stud 115 to the lapping arm 98. A transversely extending guide 116 is mounted on the lower end of the bracket 100. The guide 116 is provided with slots 117 and 117a (Figs. 14 and 15), which serve as guides for the lapping arm 98 and the follower arm 108 during a lapping operation. A tension spring 118 (Fig. 14) is connected at one end by a stud 119 with the guide 116 and bracket 100, and at the other end by a stud 120 with the follower arm 108. The spring 118 serves to maintain the follower roller 112 in operative engagement with the master cam 49. It will be readily apparent from the foregoing disclosure that when the cam shaft 28 and master cam shaft 49 are synchronously rotated, the follower roller 112 will transmit a rocking motion to the follower arm 108. The follower arm 108 through the link 113 will transmit a corresponding rocking movement to the lapping arm 98 and thereby impart a controlled movement to the lapping element 105, so that the cam 28a will be lapped to the desired and predetermined contour.

A modified form of lapping element has been illustrated in Fig. 16, comprising a pivotally mounted block 121 which is pivotally supported by the stud 115 on the lapping arm 98. The

block 121 serves as a support for a cylindrically shaped member or shoe 122. A flexible band 123 of yieldable material is supported by the block 122 and wraps around the exposed portion of the shoe 122. A strip of flexible abrasive paper or cloth 124 wraps around the outer surface of the yieldable material 123 to provide a lapping surface of a diameter at its effective surface, equal to the diameter of the follower roller 112. If desired, a continuous roll of abrasive paper or cloth may be provided, as is old and well known in the cam lapping art.

The base 20 is provided with a pair of upwardly extending brackets 125 and 126, which serve as a support for a longitudinally extending frame 127. The lower surface of the frame 127 is provided with a dovetailed slideway 128, which serves in a manner to be hereinafter described, to support the mechanism for carrying the lapping arms.

The lapping arms 95, 96, 97 and 98 are preferably arranged in pairs for a simultaneous reciprocating movement in opposite directions to impart an additional breakup motion to the lapping operation. A longitudinally movable supporting member 130 is provided for supporting the lapping arms 97 and 98, and a similar supporting member 131 is provided for supporting the lapping arms 95 and 96.

A pair of brackets 132 and 133 are provided with dovetailed lapping surfaces, which are supported on the dovetailed slideway 128 on the frame 127. The bracket 132 is pivotally connected by a stud 134 with a rock arm or frame 135. The lower end of the frame 135 is connected by a stud 140 with the supporting member 130. The bracket 133 supports a pivot stud 142, which in turn pivotally supports the upper end of a rock arm or frame 143. A stud 144 connects the lower end of the frame 143 to the other end of the supporting member 130. Flexible rubber bearings are interposed between each of the studs 134, 140, 142 and 144, and the respective ends of the frames 135 and 143, so as to provide frictionless resilient bearings so that the supporting member 130 may be readily moved in a longitudinal direction through the required stroke.

A pair of brackets 145 and 146 are provided for supporting the supporting member 131. The bracket 145 carries a stud 147, which is pivotally connected to the rock arm or frame 149. A pivot stud 151 connects the lower end of the frame 149 with one end of the supporting member 131. Similarly, the bracket 146 carries a stud 148, which is pivotally connected with the rock arm or frame 150. The lower end of the arm 150 is connected by means of a stud 152 with the other end of the supporting member 131. A flexible rubber bearing is interposed between each of the studs 147, 148, 151 and 152 and the respective ends of the frames 149 and 150, so that the supporting member 131 may be readily moved or reciprocated in a longitudinal direction to impart a breakup motion to the lapping arms 95 and 96. It will be readily apparent from the foregoing disclosure that the supporting members 130 and 131 serve as supports for pairs of brackets 100—100a and 100b—100c. In setting up the machine for lapping a given cam shaft 28, the brackets 100 may be adjusted longitudinally on the supporting members 130 and 131, so as to align the lapping elements and follower rollers with the respective cams on the cam shaft to be lapped and the master cam shaft.

In order to transmit a simultaneous reciprocating movement to the supporting members 130 and 131, a motor driven mechanism is provided comprising a motor 155, which is provided with a motor pulley 156. The motor pulley 156 is connected by multiple V-belts 157 with a multiple V-groove pulley 158. The pulley 158 is supported on one end of a rotatable shaft 159. The shaft 159 is rotatably journaled in bearings 160, 161 and 162, which are supported by a frame 163. The frame 163 is adjustably clamped to the bracket 127. A pair of opposed eccentrics 164 and 165 (Fig. 12) are keyed to the shaft 159. The eccentric 165 is connected by a connecting rod 167 with a stud 168. The stud 168 is carried by a bracket 170, which is fastened to the rock arm 135. Similarly, the eccentric 164 is connected by a connecting rod 166 with a pivot stud 169, which is carried by a bracket 171 fastened to the rock arm 150. It will be readily apparent from the foregoing disclosure that when the motor 155 is started, the shaft 159 will rotate the eccentrics 164 and 165 and impart a simultaneous reciprocating movement in opposite directions through the mechanism above described to the supporting members 130 and 131, and also to the lapping arms and elements supported thereby. The reciprocating movement of the lapping elements is provided for a breakup motion, to provide a more efficient lapping action between the lapping element and the cam being lapped. The reciprocating stroke of the lapping elements is relatively short, and preferably does not exceed $\frac{1}{8}$ of an inch. Therefore, even though a swinging motion is provided for the supporting members 130 and 131, due to the relatively short stroke, these supporting members, together with the lap supported thereby, will move through a substantially rectilinear path.

To facilitate control of the electric motors, a push button switch 175 is provided for controlling the work drive motor 30. A push button switch 176 is provided for controlling the table reciprocating motor 81 and a push button switch 177 is provided for controlling the lap arm reciprocating motor 155.

It will thus be seen that there has been provided by the invention apparatus in which the various objects hereinabove set forth, together with many thoroughly practical advantages, are successfully achieved. As many possible embodiments may be made of the above invention, and as many changes might be made in the embodiments above set forth, it is to be understood that all matter hereinbefore set forth or shown in the accompanying drawings is to be interpreted as illustrative and not in a limiting sense.

I claim:

1. In a cam lapping machine having a reciprocable table, means to reciprocate said table, a headstock and footstock on said table, a pair of rotatable parallel spindles on said headstock, a pair of aligned parallel footstock centers on said footstock rotatably to support a master cam shaft and a cam shaft to be lapped in parallel relationship with each other, means to synchronously rotate said spindles, a pivotally mounted follower arm having a master cam follower roller which engages a master cam, yieldable means to maintain said roller in operative engagement with the master cam, a pivotally mounted lapping arm having a yieldably mounted lapping element engageable with a cam to be lapped, a guide for said follower and lapping arms, and a link connecting said arms whereby a controlled swing-

ing movement is imparted to the lapping element.

2. In a cam lapping machine having a reciprocable table, means to reciprocate said table, a headstock and a footstock on said table, a pair of rotatable parallel spindles on said headstock, a pair of aligned parallel footstock centers on said footstock rotatably to support a master cam shaft and a cam shaft to be lapped in parallel relationship with each other, means including an electric motor to synchronously rotate said spindles, a pivotally mounted follower arm having a master cam follower roller which engages a master cam, yieldable means to maintain said roller in operative engagement with the master cam, a pivotally mounted lapping arm having a yieldably mounted lapping element engageable with a cam to be lapped, a guide for said follower and lapping arms, a link connecting said arms whereby a controlled swinging movement is imparted to the lapping element, and means to reciprocate said follower and lapping arms.

3. In a cam lapping machine having a base, a headstock and a footstock, means rotatably to support a cam shaft to be lapped thereon, a synchronously rotated master cam shaft which is arranged parallel to the cam shaft to be lapped, a longitudinally reciprocable table, spaced pivotally mounted arms to support said table so that it may be reciprocated longitudinally in a substantially rectilinear path, means including a motor driven crank pin to reciprocate said table, a pivotally mounted cam lapping arm having a lapping element thereon, a pivotally mounted follower arm having a follower roller thereon which is arranged to engage a master cam, said lapping and follower arms being arranged parallel to each other, a link pivotally connecting said arms so that a controlled swinging movement is transmitted by the follower arm to the lapping arm and element, and yieldable means between said lapping element and lapping arm whereby the lapping element is yieldably maintained in lapping engagement with the cam being lapped during a lapping operation.

4. In a cam lapping machine having a base, a pair of spaced upwardly extending brackets adjacent to the opposite ends of the base, a pivotally-mounted pendulum-type arm suspended from each of said brackets, a longitudinally movable table, pivotal connections between the opposite ends of the table and the lower ends of said arms so as to facilitate a longitudinal reciprocatory movement of the table, a motor driven adjustable pitman to impart a relatively short reciprocatory stroke to said table, a rotatable work support on said table including a pair of parallel synchronously rotated spindles and footstock centers to support a cam shaft to be lapped and a master cam shaft, a pivotally mounted follower arm having a follower roller which is arranged to engage a master cam, a pivotally mounted lapping arm having a lapping element yieldably mounted thereon, operative connections between said arms, a supporting member for both of said arms, and means to reciprocate said member to impart a reciprocatory motion to said master cam roller and said lapping element relative to the cam being lapped.

5. In a cam lapping machine as claimed in claim 4, in combination with the parts and features therein specified, of a bracket adjustably clamped to the underside of the supporting member, a follower arm pivotally suspended from said bracket, a follower roller on said arm to en-

gage a master cam, a lapping arm pivotally suspended to the underside of the supporting member, said lapping arm being spaced from and substantially parallel to the follower arm, a lapping element yieldably supported adjacent to the lower end of said lapping arm, a connecting link pivotally connecting both of said arms so that a controlled rocking movement is transmitted by the follower roller to the lapping element, and a guide fixedly mounted on said bracket to guide the swinging movement of said follower and lapping arms.

6. In a cam lapping machine having a base, a pair of spaced upwardly extending brackets adjacent to the opposite ends thereof, a pivotally-mounted pendulum-type arm suspended from each of said brackets, a longitudinally movable table, pivotal connections between the opposite ends of the table and the lower ends of said arms so as to facilitate a longitudinal reciprocatory movement of the table, a motor driven adjustable pitman to impart a relatively short reciprocatory stroke to said table, a rotatable work support on said table including a pair of parallel synchronously rotated spindles and footstock centers to support a cam shaft having a plurality of cams to be lapped and a master cam shaft having a plurality of master cams, a plurality of spaced pivotally mounted follower arms each having a follower roller which is arranged to engage one of said master cams, a plurality of spaced pivotally mounted lapping arms each having a lapping element yieldably mounted thereon yieldably to engage one of said cams to be lapped, operative connections between said follower and said lapping arms, an oscillatable supporting member to support said followers and lapping arms, and means to oscillate said member to impart a reciprocatory motion to said master cam rollers and said lapping elements relative to the cams being lapped.

7. In a cam lapping machine having a base, a pair of spaced upwardly extending brackets adjacent to the opposite ends thereof, a pivotally-mounted pendulum-type arm suspended from each of said brackets, a longitudinally movable table, pivotal connections between the opposite ends of the table and the lower ends of said arms so as to facilitate a longitudinal reciprocatory movement of the table, a motor driven adjustable pitman to impart a relatively short reciprocatory stroke to said table, a rotatable work support on said table including a pair of parallel synchronously rotated spindles and footstock centers to support a cam shaft having a plurality of cams to be lapped and a master cam shaft having a plurality of master cams, a plurality of pivotally mounted follower arms having follower rollers which are arranged to engage said master cams, a plurality of pivotally mounted lapping arms each having a lapping element yieldably mounted thereon yieldably to engage said cams to be lapped, said follower and lapping arms being arranged in pairs, operative connections between said follower and said lapping arms, a pair of spaced supporting members each arranged to support a plurality of pairs of followers and lapping arms, and means simultaneously to reciprocate said members in opposite directions to impart a reciprocatory motion to said master cam roller and said lapping element relative to the cams being lapped.

8. In a cam lapping machine as claimed in claim 7, in combination with the parts and features therein specified, of a pair of opposed rotat-

11

able eccentrics, connecting rods to connect each of said eccentrics with one of said supporting members, and an electric motor positively to rotate said eccentrics simultaneously to reciprocate said members in opposite directions so as to impart a reciprocatory movement to said lapping elements relative to the cams being lapped.

9. In a cam lapping machine as claimed in claim 7, in combination with the parts and features therein specified, of a pair of spaced pivotally-mounted pendulum-type arms to support each of said supporting members, a rotatable drive shaft, a pair of diametrically opposed eccentrics on said shaft, and connecting rods to connect each of said eccentrics with one of said arms to impart a swinging motion thereto and thereby to reciprocate said members simultaneously in opposite directions.

10. In a cam lapping machine as claimed in claim 7, in combination with the parts and features therein specified, of a longitudinal dovetailed slide way formed on the underside of said supporting member, a plurality of spaced depending brackets adjustably clamped on said dovetailed slide way, a pair of pivotally mounted downwardly extending parallel arms on each of said brackets, a link pivotally connected adjacent to the lower end of each of said arms, a follower roller adjacent to the lower end of one of said arms which is arranged to engage a master cam, a lapping element yieldably mounted adjacent to the lower end of the other of said arms, a guide on said bracket to guide both of said arms, and means including a spring interposed between said bracket and follower arm to maintain said follower in operative engagement with a master cam so as to impart a controlled movement to said lapping element during a lapping operation.

11. In a cam lapping machine having a base, a longitudinally reciprocable table, a rotatable work support including a headstock and a footstock on said table; an anti-friction support for said table comprising a pair of spaced brackets adjacent to the opposite ends of said base, pivotally supported substantially vertical arms depending from said brackets, flexible rubber bearings interposed between said brackets and arms, flexible rubber bearings connecting the lower ends of said arms with the opposite ends of said table, and means to impart a relatively short reciprocatory stroke to said table, said rubber bearings being sufficiently resilient so that the arms may be rocked relative to the brackets and table during reciprocation of the table.

12. In a cam lapping machine as claimed in claim 11, in combination with the parts and features therein specified, of a frame, a reciprocable supporting member, a pair of pivotally mounted rock arms to support said member, flexible rubber bearings connecting said rock arms with said frame, flexible rubber bearings connecting the lower ends of said arms with the opposite ends of said supporting member, means to reciprocate said member, a plurality of adjustable brackets on said supporting member, a pair of pivotally mounted arms depending from each of said brackets, a flexible rubber bearing connecting said arms with said bracket, a master cam follower roller on one arm of each pair of said arms, a lapping element on the other arm of each pair of said arms, said rubber bearings being sufficiently flexible so that the arms may rock through predetermined limits, a guide on each of said brackets to guide the follower and lap-

12

ping arms supported thereby; and a connecting link pivotally connected at its opposite ends to the follower and lapping arms whereby a controlled rocking movement of the follower arms is transmitted to impart a controlled rocking movement to said lapping arms and elements.

13. In a cam lapping machine as claimed in claim 11, in combination with the parts and features therein specified, of a frame, a pair of reciprocable supporting members, a pair of pivotally mounted rock arms to support said members, flexible rubber bearings connecting said rock arms with said frame, flexible rubber bearings connecting the lower ends of said arm with the opposite ends of said supporting members, means to reciprocate said members, a plurality of adjustable brackets on each of said supporting members, a pair of pivotally mounted arms depending from each of said brackets, a flexible rubber bearing connecting said arms with said brackets, a master cam follower roller on one arm of each pair of said arms, a lapping element on the other arm of each pair of said arms, said rubber bearings being sufficiently flexible so that the arms may rock through predetermined limits, a guide on each of said brackets to guide the follower and lapping arms supported thereby, and a connecting link pivotally connected at its opposite ends to the follower and lapping arms whereby a controlled rocking movement of the follower arms is transmitted to impart a controlled rocking movement to said lapping arms and elements.

14. In a cam lapping machine having a base, a pair of upwardly extending brackets at opposite ends of the base, a pair of vertically arranged arms pivotally supported on said brackets, a longitudinally reciprocable work table, pivotal connections between the opposite ends of said table and the lower ends of said arms whereby the table may be reciprocated in a substantially rectilinear path through a relatively short stroke, flexible rubber bearings between said brackets and arms and between said arms and table, the resilience of said rubber serving to facilitate a reciprocatory movement of said table, and means including a motor driven adjustably mounted crank pin which is operatively connected to reciprocate said table.

15. In a cam lapping machine having a base, a pair of upwardly extending brackets at opposite ends of the base, a pair of vertically arranged arms pivotally supported on said brackets, a longitudinally reciprocable table, pivotal connections between opposite ends of said table and the lower ends of said arms whereby the table may be reciprocated in a substantially rectilinear path through a relatively short stroke, flexible rubber bearings between said brackets and arms and between said arms and table, the resilience of said rubber serving to facilitate a reciprocatory movement of said table, means including a motor driven adjustable crank pin which is operatively connected to reciprocate said table, and a pair of spaced parallel transversely extending links interposed between the base and table, one end of each of said links being connected by a flexible rubber bearing to the table, and the other end of each link being connected by a flexible rubber bearing with the base, said links and bearings serving to guide and steady said table against transverse movement during reciprocation thereof.

16. In a cam lapping machine having a base, a pair of upwardly extending brackets at opposite

ends of the base, a pair of vertically arranged arms pivotally supported on said brackets, a longitudinally reciprocable work table, pivotal connections between the opposite ends of said table and the lower ends of said arms whereby the table may be reciprocated in a substantially rectilinear path through a relatively short stroke, and flexible rubber bearings connecting said brackets to said arms and said arms to said table, the outer periphery of the bearings being fixed to said arms and the inner periphery of the bearings being fixed to the brackets and table respectively, said rubber bearings being sufficiently flexible so that the arms may swing through predetermined limits.
